UNITED STATES PATENT OFFICE.

CHARLES H. JULL, OF RIPLEY, NEW YORK.

MEAT-CUTTER.

No. 906,032.

Specification of Letters Patent.

Patented Dec. 8, 1908.

Application filed April 1, 1907. Serial No. 365,731.

To all whom it may concern:

Be it known that I, CHARLES H. JULL, a citizen of the United States, residing at Ripley, in the county of Chautauqua and State 5 of New York, have invented certain new and useful Improvements in Meat-Cutters; and I do hereby declare the following to be a full, clear, and exact description of the invention, such as will enable others skilled 10 in the art to which it appertains to make and use the same, reference being had to the accompanying drawings, and to the letters of reference marked thereon, forming part of this specification.

15 My invention relates to meat-cutters and has for its object certain improvements in their construction whereby greater facility of adjustment of the parts is attained, and improved efficiency secured.

20 The features of my invention are herein-after fully set forth and described, and illustrated in the accompanying drawings in which:

Figure 1 is a top or plan view of my improved meat-cutter. Fig. 2 is a vertical central section of the same on the line $x-x$ in Fig. 1. Fig. 3 is a detail of a section of the machine. Fig. 4 is a detail showing a modified construction of the cutter-bowl actuating mechanism. Fig. 5 is a detail section of the bowl adjusting mechanism. Fig. 6 is a bottom view of my improved meat-cutter with the legs thereof broken away.

In these drawings illustrating my invention A is the upright portion of the machine frame upon which is secured a circular top portion A'. In bearings B on the under surface of the circular part A' of the frame, I mount rollers B' which support and carry 35 a cutter-bowl D; this bowl D being provided at its upper edge with a radial flange d which rests upon the rollers B'. And in radially adjustable bearings C in the top of the circular portion A' of the frame, I 40 mount rollers C', which operate against the peripheral edge of the flange d on the bowl D, so that the bowl D may be adjusted laterally in the circular portion A' of the frame as desired.

45 Across the top of the circular part A' of the frame, I secure a cross-bar E and in a bearing e thereon and a bearing a on the part A' of the frame, I mount a cutter wheel shaft F, provided on its outer end with a 50 driving pulley f and on its inner end with a curved knife blades f' which operate through

a slot e' in the cross-bar E, and down into the cutter-bowl D at one side of the center thereof, as clearly shown in Fig. 2, and over the cutter-blades f' I secure to the cross-bar E a removable cover E' to cover and protect the blades f'. The central part of the bottom of the cutter-bowl D is curved upward to a central point D', so that the curve of the inside of the bottom of the 60 cutter-bowl D, from its center point D' to the rim thereof coincides with the circle traversed by the ends of the cutter-blades f'. The central portion of the bottom of the bowl D is formed of a removable section D² 70 hinged at one side to ears d', and is adapted to be secured to the bowl D at its opposite side, by means of an eccentric latch G pivoted on a lug d² on the bottom of the bowl D; the latch G being provided with an arm 75 G' for operating the same. This hinged bottom section D² of the cutter-bowl D enables the operator to quickly and easily discharge the contents of the cutter-bowl into a suitable receptacle when desired. 80

For rotating the cutter-bowl D so as to bring its contents under the cutter-blades f', I provide a worm-rack H on the under surface of the rim d of the bowl, in which a worm I operates, as clearly shown in Figs. 85 2 and 3. The shaft I' carrying the worm I is mounted at its outer end in a pivoted bearing I² on a lug a' on the part A' of the frame, and is provided with a pulley I³ from which a belt K extends to a pulley f² 90 on the cutter-wheel shaft F for operating the shaft I'. The opposite or inner end of the shaft I' is mounted in a horizontally sliding bearing J on the machine frame, and in ears d² on the part A' of the frame there 95 is pivoted a bell-crank lever L, one arm l of which is pivoted to the sliding bearing J and the other arm l', is used as an operating lever, whereby the worm I can be drawn back out of mesh with the worm-rack H, 100 when it is desired to suddenly stop the rotation of the bowl D.

In Fig. 4 I show a modified form of adjustable support for the cutter-bowl D. In this case on the under side of the flange d 105 I provide a downwardly projecting flange d³, and the supporting rollers B' which are provided with bearings B², which bearings are radially adjustable with relation to the axis of the cutter-bowl D, whereby said bowl 110 can be laterally adjusted as desired.

In Fig. 5 I show a modification of the

form of the supports and of the adjustment of the radially adjustable rollers C'. In this construction the roller supports C² are made integral with the part A' of the frame and are provided with radial slots c in which the bearings C³ of the rollers C' are adjustably secured by means of nuts c'.

Having thus described my invention so as to enable others to construct and use the same, what I claim as new and desire to secure by Letters-Patent from the United States is:

1. The combination in a meat-cutter, of a frame, a cutter bowl, having a radial flange on the upper edge of the bowl, rollers on said frame under said flange for supporting the bowl, rollers radially adjustable with reference to the center of rotation of the bowl operating against the periphery 20 of the flange of the bowl whereby it can be laterally adjusted, a rotating cutter operating in said bowl, and means for rotating said bowl on its roller supports, substantially as set forth.
2. The combination in a meat-cutter, of a frame, a cutter-bowl, rollers mounted thereon under the periphery of the bowl upon which it is supported and rotates,

rollers radially adjustable on said frame with reference to the center of rotation of the bowl contacting with the edge of the bowl whereby the bowl can be laterally adjusted and is supported against lateral movement, a cutter-wheel mounted on the frame so as to operate in the cutter-bowl at one side of the center thereof, means for rotating the cutter-bowl, and means for stopping its rotation, substantially as set forth.

3. In a meat cutter, a frame, a cutter-bowl, having a peripheral flange thereon, rollers in the frame upon which the flange of the cutter-bowl rests, roller supports radially adjustable in said frame with reference to the center of rotation of the bowl, rollers mounted in said supports and contacting with the periphery of the flange on the bowl whereby the bowl can be laterally adjusted, and means for rotating the cutter-bowl, substantially as set forth.

In testimony whereof I affix my signature, in presence of two witnesses.

CHARLES H. JULL.
